UNITED STATES PATENT OFFICE.

MARSHALL C. LEFFERTS, OF NEW YORK, N. Y., ASSIGNOR TO THE CELLULOID COMPANY, A CORPORATION OF NEW JERSEY, OF SAME PLACE.

DESIGN FOR A RAZOR-HANDLE.

SPECIFICATION forming part of Design No. 26,783, dated March 23, 1897.

Application filed February 3, 1897. Serial No. 621,891. Term of patent 7 years.

To all whom it may concern:

Be it known that I, MARSHALL C. LEFFERTS, a citizen of the United States, residing in the city, county, and State of New York, have invented and produced a new and useful Design for Razor-Handles and the Like, of which the following is a specification.

My invention relates to designs for razor-handles and the like; and it consists in the article provided with the ornamentation, substantially as hereinafter described.

In the drawings forming part of this invention, Figure 1 is a side elevation, and Fig. 2 an end elevation, of a razor-handle ornamented by my design.

The handle, of conventional form, is ornamented on the exterior of its two parts 1 2 as follows: At the edge and between the ends

is produced a row or range of beads 3, their bases being depressed below the surface of the parts 1 2, which is slightly convex centrally, as shown in Fig. 2. At the ends of the parts 1 2 and on the edges are produced the foliated figures 4 5 in relief, each figure having an intermitting bead 6 7 at their junction and meeting the range of beads 3 at their inner ends.

Having described my invention, I claim--

The design for razor-handles and the like, substantially as herein shown and described. 30

Signed at the city, county, and State of New York, this 2d day of February, 1897.

MARSHALL C. LEFFERTS.
